UNITED STATES PATENT OFFICE.

NICHOLAS W. CEASE, OF RICHMOND, VIRGINIA, ASSIGNOR TO THE AMERICAN AUTOMATIC FAN COMPANY, OF SAME PLACE.

FAN ATTACHMENT FOR SEWING-MACHINES.

SPECIFICATION forming part of Letters Patent No. 681,193, dated August 27, 1901.

Application filed November 8, 1900. Serial No. 35,864. (No model.)

To all whom it may concern:

Be it known that I, NICHOLAS W. CEASE, a citizen of the United States, residing at Richmond, in the county of Henrico and State of 5 Virginia, have invented new and useful Improvements in Fan Attachments for Sewing-Machines, of which the following is a specification.

This invention relates to new and useful 10 improvements in fan attachments for sewing-machines; and its primary object is to provide a device of simple construction which can be easily connected to the arm of a sewing-machine of any make and which is so secured 15 thereto as to prevent injury by scratching or in any other similar manner.

A further object is to so construct the device that the same may be readily taken apart for convenience in packing.

20 Another object is to provide means whereby the fan may be adjusted back and forth within its standard, so as to bring a pulley which is secured thereto in vertical alignment with the driving-pulley.

25 A further object is to provide a fan of novel construction for use in connection with the attachment.

With these and other objects in view the invention consists in providing a base-plate 30 which is provided at suitable intervals with threaded apertures, any one of which is adapted to receive the lower threaded end of a standard. Any one of these apertures is also adapted to receive a screw which is adapted 35 to secure a clip to the base. This clip, as well as the base, is provided with soft protecting material, as felt, whereby injury to the arm to which the attachment is secured is prevented. One of the remaining apertures within the base is adapted to receive 40 the spool-spindle of the arm in order that the attachment may be held securely in position. A sleeve is arranged at the upper end of the standard and is adapted to receive a tube, said tube being locked within the sleeve by means of a set-screw. A spindle is revolvable within the tube and is provided at one end with a pulley, while the opposite end is

detachably secured to a cylindrical hub having longitudinally-extending slots therein arranged in planes at right angles to each other. These slots are adapted to receive interlocking fan-blades, which extend from the cylinder at right angles to each other, and the outer end of said cylinder is threaded and is 55 adapted to project into a nut which serves to bind the slotted end of the cylinder together and also prevents the accidental removal of the fan-blades.

The invention also consists in the further 60 novel construction and combination of parts, which will be hereinafter more fully described and claimed, and illustrated in the accompanying drawings, showing the preferred form of my invention, and in which—

65 Figure 1 is a perspective view showing my fan attachment in position upon the arm of a sewing-machine. Fig. 2 is a vertical section through the attachment. Fig. 3 is an enlarged section through the hub of the fan, 70 showing the fan-blades in position therein. Fig. 4 is a detail view of the hub detached. Fig. 5 is a similar view of a fan-blade.

75 Referring to the drawings by numerals of reference, 1 is the arm of a sewing-machine, having a spool-spindle 2 extending upward therefrom. This spindle is adapted to project through any one of a series of threaded perforations 3, formed within the base-plate 4 of my improved attachment. Secured to 80 the lower surface of this plate is a pad 5, preferably wedge-shaped in side elevation and formed of any suitable material, as rubber or felt. This pad is also provided with apertures therein which are adapted to register 85 with the apertures within the base-plate. A clip 6, formed of spring metal, extends over the base-plate 4 and downward therefrom, the ends of said clip being bent toward each other, so as to extend under the arm 1. 90 Downward extensions 7 are arranged at the ends of the clip, and each extension has a series of perforations 8 for the reception of suitable securing means, as a thumb-screw 9. This clip is provided upon its inner surface 95 with a covering 10, of felt or other similar

material, and is secured to the base-plate 4 by means of a screw 11, which is adapted to engage the walls of any one of the perforations 3. Fitted within one of these perforations 5 is the threaded end of a standard 12, to the upper end of which is secured a sleeve 13. A set-screw 14 is arranged within this sleeve and is adapted to bind upon a tube 15, fitted within the sleeve. It will be readily seen that when the set-screw 14 is turned outward this tube may be slipped longitudinally within the sleeve and after reaching the desired position may be locked by said screw. A spindle or rod 16 is revolvable within the tube 15. A pulley 17 is secured at one end of this rod, while the opposite end is threaded and extends into one end of the tubular hub 18 of the fan proper. This tube is slotted from one end to a point adjacent to the inner end thereof, said slots 19 intersecting and being arranged in planes at right angles to each other. Each of the slots is adapted to receive one of the sections 20 of the fan. Each of these sections, as shown in Fig. 5, 25 forms two of the fan-blades and is constructed of a single piece of sheet metal or similar material having a longitudinally-extending slot 21 at the center thereof and extending for one-half of its length. The slots 21 within 30 in the two portions 20 of the fan extend inward from opposite edges thereof, and these slots permit the blades to interlock, as shown in Fig. 2. The blades are then slipped into the intersecting slots 19 of the hub 18 and the outer end 22 of the hub is placed into engagement with a nut 23, which serves to bind said end together and also prevents the accidental displacement of the blades. If desired, the inner edges of the plates 20 may be recessed, 35 as shown at 24, so as to extend for a desired distance beyond the inner ends of the slots 19 in the hub. 40

The pulley 17 upon the rod 16 receives motion through a belt or cord 25 from a second pulley 26, mounted at the center of the hand-wheel 27 of the sewing-machine. This pulley 26 may also be employed for throwing the mechanism within the arm of the sewing-machine into or out of engagement with the operating mechanism. 50

It will be seen that when the attachment is to be used upon sewing-machine arms having the spool-spindle arranged at a greater or less distance from the hand-wheel 27 it is only necessary to place the spindle 2 in the proper aperture 3 within the base-plate. Moreover, the clip 6 can be adjusted to the arm at any point thereon by simply placing the thumb-bolt 9 within the proper aperture 8. The standard 12 may be placed in the desired aperture 3, and by providing the adjustable tube 15 the pulley 17 may be slid back or forth until the same arrives in vertical alinement with the pulley 26. 60

65 The fan is extremely simple in construction

and durable, and the blades may be readily detached when it is desired to pack the device.

By providing a wedge-shaped pad, as 5, the base-plate is held at all times in a horizontal position and, moreover, securely grips the arm upon which it rests. 70

In the foregoing description I have embodied the preferred form of my invention; but I do not wish to be understood as limiting myself thereto, as I am aware that modifications may be made therein without departing from the principle or sacrificing any of the advantages of this invention, and I therefore reserve to myself the right to make such changes as fairly fall within the scope thereof. 75

Having thus described the invention, what is claimed, and desired to be secured by Letters Patent, is— 85

1. The combination with a base-plate having a series of threaded apertures therein; of an adjustable clip for securing the base-plate upon a sewing-machine arm, means extending into one of said apertures for detachably securing the clip to the base-plate, a standard 90 detachably secured within one of the apertures, a sleeve upon the standard, a tube slidably mounted within the sleeve, means for locking the tube in said sleeve, a rod revolvable within the tube, a pulley at one end of the rod, and a fan secured to the remaining end of said rod. 95

2. The combination with a base-plate having a series of threaded apertures therein; of an adjustable clip for securing the base-plate, means extending into one of the threaded apertures whereby the clip is detachably secured to the base-plate, a standard detachably secured within one of the apertures, a sleeve thereon, a tube adjustably secured within the sleeve, a rod revolvable therein, a pulley at one end of the rod, a hub detachably secured to the remaining end of the rod, and fan-blades extending from said hub. 100 105 110

3. In an attachment of the character described, a fan comprising a hub having intersecting longitudinally-extending slots therein, interlocking fan-blades within the slots and extending therefrom, threads upon the slotted end of the hub, and a nut engaging the threads and adapted to bind said end together. 115

4. In an attachment of the character described, the combination with a standard; of a sleeve thereto, a tube adjustably secured within the sleeve, a rod revolvable within the tube, a pulley at one end of the rod, a hub adapted to be engaged at one end by the remaining end of the rod, said hub having longitudinally-extending intersecting slots therein, interlocking fan-blades within said slots and extending therefrom, threads upon the slotted end of the hub, and a nut engaging the threads and adapted to bind said end to- 120 125 130

gether and prevent displacement of the fan-blades.

5. A fan attachment for sewing-machines comprising a base-plate having an aperture therein adapted to receive the spool-spindle of the arm of a sewing-machine, a clip adapted to clasp said arm to secure the base-plate thereto, a standard upon the base-plate, a rev-

oluble rod upon the standard and a fan secured to said rod.

In testimony whereof I affix my signature in presence of two witnesses.

NICHOLAS W. CEASE.
